FLAP HOLDING DEVICE FOR CARTONS
Phillip B. Mayer, 2029 E. Newport Ave., Milwaukee, Wis.
Filed June 20, 1961, Ser. No. 118,465
8 Claims. (Cl. 53—381)

This invention relates to a flap holding device for cartons and more particularly to a device for firmly holding the overlapping flaps of a partially filled container so that the flaps can be stapled or otherwise fastened together.

Cardboard cartons are generally fabricated with an open top and four flaps are folded over to enclose the open top of the carton. The normal procedure in joining the flaps together to seal the container is to staple or otherwise mechanically fasten the flaps together. However, when the carton is only partially filled, the contents of the carton will not provide a bearing surface for the stapling device and therefore it is not possible to staple the overlapping flaps of a partially filled carton. Normally, the flaps of a partially filled carton are sealed by gummed tape. The taping operation requires a considerably greater period of time than stapling and the tape does not provide a seal which is as strong as staples or mechanical fasteners.

The present invention is directed to a device for holding the overlapping flaps of a carton so that the flaps may be stapled or otherwise fastened together. More particularly, the device comprises a thin elongated tube which is adapted to be inserted within the carton through the opening between the folded flaps. A collapsible wing is folded against the thin tube when the same is inserted within the opening between the flaps, and after the wing has passed within the container it is automatically expanded to a position generally normal to the axis of the tube. In addition to the collapsible wing, a fixed wing is also connected to the tube which is biased against the outer surface of the flaps so that the flaps are firmly held between the inner collapsible wing and the outer wing. With the flaps held in this position and supported by the inner wing, the flaps can be readily stapled together by use of a stapling gun.

The present device is easily inserted within the opening between the folded flaps and will not enlarge the opening to any extent. The flaps are firmly held in the overlapping position by the wings which are located on the inner and outer surfaces of the flaps. While held in this manner, the flaps can be readily fastened together by stapling or other mechanical fastening means.

In addition, the collapsible wing can be readily folded against the thin tube after the stapling operation so that the entire tube can be readily removed from the container.

Other objects and advantages will appear in the course of the following description.

The drawings illustrate the best mode presently contemplated of carrying out the invention.

In the drawings:

FIG. 1 is a perspective view of a cardboard carton with the flap holding device being inserted within the opening between the folded flaps;

FIG. 2 is a side elevation of the flap holding device with parts broken away in section and showing the collapsible wing in the extended holding position;

FIG. 3 is a reduced transverse section taken along line 3—3 of FIG. 2;

FIG. 4 is a reduced transverse section taken along line 4—4 of FIG. 2 with the carton flap removed;

FIG. 5 is a view taken along line 5—5 of FIG. 2; and

FIG. 6 is a fragmentary view similar to FIG. 2 showing the collapsible wing in the collapsed position.

2

The drawings illustrate a container or carton 1 formed of cardboard or other similar material and which includes a pair of side walls 2 and end walls 3. The carton 1 has an open top which is adapted to be enclosed by four flaps 4 which are folded downwardly over the open top.

As shown in FIG. 1, the flap holding device 5 of the invention is inserted within the small opening between the overlapping flaps 4 of the carton 1 and is adapted to hold the overlapping flaps in tight engagement for stapling or other mechanical fastening operations.

The flap holding device 5 includes a thin elongated outer tube 6 having a pair of diametrically opposite slots 7 which extend substantially the length of the tube. The upper end of the tube 6 is threaded and is received within a threaded recess 8 in a hand knob 9.

The lower end of the tube 6 is cut diagonally with respect to the axis of the tube and is provided with a small projecting tip 10.

A rod 11 is located within the tube 6 and the lower end of the rod is formed integrally with a slide 12 which is adapted to slide within the tube 6. The upper end of the rod is threadedly received within an opening in a central slide 13 and the slide 13 is biased downwardly by a spring 14 which is interposed between the slide 13 and the hand knob 9.

The central slide 13 is provided with an opening in alignment with the slots 7 and a finger loop 15 is disposed within the opening and extends laterally outward through the slot 7. The fingers of the operator are adapted to be engaged within the loop 15 and by drawing the fingers upwardly against the palm of the hand which engages the hand knob 9, the slide 13 and rod 6 will be drawn upwardly within the tube against the force of the spring 14.

An annular collar 16 is slidably disposed around the rod 11 and a spring 17 is disposed between the collar 16 and the slide 13 and functions to bias the collar downwardly toward the lower end of the rod. A pair of wings 18 are secured to the collar 16 and extend outwardly through the slots 7.

A yoke 19 is pivotally secured to the slide 12 by a pin 20 which extends through the slots 7. A pair of wings 21, similar in construction to wings 18, are secured to the yoke and in the flap holding position extend normally to the axis of the rod 11 and are displaced 90° from the wings 18. To maintain the wings 21 in the extended position normal to the axis of the rod 11, a coil spring 22 is disposed around the pin 20 and one end of spring 22 is secured within an opening in recess 23 formed in the lower end of slide 12 and the other end of the spring is secured with an opening in yoke 19.

In operation of the device, the loop 15 is initially pulled upwardly toward the hand knob 8 by the operator which compresses the spring 14 and moves the slides 12 and 13 upwardly as well as the collar 16. As the slide 12 is pulled upwardly, one of the wings 21 engages the tip 10 on the tube causing the wings to tilt. Further upward movement of the slide 12 causes the wings 21 to collapse against the side of the tube as shown in FIG. 6. With the wings 21 disposed flatwise against the side of the tube, the tube is inserted within the opening between the flaps 4. As the tube is inserted within the opening, the wings 18 engage the outer surface of the flaps and are moved upwardly toward slide 13, thereby compressing the spring 14.

When the device has been inserted sufficiently far within the carton to permit the wings 21 to be extended, the loop 15 is released and the spring 14 will move the slides 12 and 13 downwardly and thereby cause the yoke 19 to move toward the end of the tube. The small spring 22

will automatically return the wings 21 to the extended position when the yoke reaches the end of the tube.

With the wings in the extended position, the device is then raised until the extended wings 21 engage the lower surface of the flaps 4 and the spring 17 at this time will urge the outer wings 18 against the outer surface of the flaps so that the flaps are tightly held between the wings 18 and 21, as shown in FIG. 2.

With the flaps being firmly held, a stapler or other mechanical fastening device can then bear against the flaps to attach the flaps together.

After the stapling operation has been completed, the device can be removed by initially pushing down on the device so that the wings 21 will be located a sufficient distance beneath the flaps so that they can be collapsed against the side of the tube. The loop 15 is then pulled upwardly, moving the slides 12 and 13 upwardly and causing the wings 21 to collapse against the side of the tube and enabling the tube to be withdrawn from the hole between the flaps.

The thin elongated flap holder of the invention can be readily inserted within the small openings between the flaps in the normal cardboard carton without danger of enlarging this opening. The inner wings automatically extend once the wings are disposed within the container so that the flaps are firmly held between the inner and outer wings during the stapling operation. Similarly, the device can be readily withdrawn from the container after stapling by merely pushing the device inwardly and collapsing the inner wings against the tube.

Various modes of carrying out the invention are contemplated as being within the scope of the following claims particularly pointing out and distinctly claiming the subject matter which is regarded as the invention.

I claim:

1. A device for firmly holding the folded overlapping flaps of a partially filled container while the flaps are mechanically fastened together, comprising an elongated member having a first end portion and a second end portion with said first end portion adapted to be disposed within an opening between the folded flaps and the second end portion adapted to be disposed outside of the container when the device is in the operative holding position, a collapsible holding member pivotally connected to said first end portion and disposed to be moved from a collapsed position in general alignment with the axis of the elongated member to an extended position generally normal to the axis of the elongated member, means disposed at said second end portion and operably connected to the collapsible holding member and adapted to be actuated by an operator for moving the collapsible member to said collapsed position to enable the elongated member to be inserted within the opening between the flaps, and a fixed holding member disposed generally normal to the axis of the elongated member and connected to the elongated member at a location between said collapsible holding member and said second portion with said fixed holding member adapted to engage the outer surface of the folded flaps and the collapsible holding member adapted to engage the inner surface of the folded flaps to thereby firmly hold the flaps together for fastening.

2. A device for firmly holding the folded overlapping flaps of a partially filled container while the flaps are mechanically fastened together, comprising an elongated tubular member having an inner portion adapted to be disposed within an opening between the folded flaps and having an outer portion adapted to be located outwardly of the container, a slide slidably disposed within the tubular member, a collapsible holding member having its central portion pivotally secured to said slide and disposed to be moved from an extended position in which the ends of said collapsible member extend laterally outward from the tubular member in at least two different directions to a collapsed position generally parallel to the

axis of the tubular member as the slide is moved toward the outer portion of the tubular member, operating means connected to the slide for moving the slide outwardly within the tubular member to thereby pivot the collapsible holding member to the collapsed position, and means operably connected to the collapsible holding member for pivoting the same to the extended position as the slide is moved to the inner portion of the tubular member.

3. A device for firmly holding the folded overlapping flaps of a partially filled container while the flaps are mechanically fastened together, comprising an elongated tubular member having an end disposed at an acute angle to the axis thereof and said end adapted to be disposed within an opening between the folded flaps and having the opposite end portion adapted to be located outwardly of the container, a slide slidably disposed within the tubular member, collapsible holding means including a yoke disposed around the tubular member and pivotally connected to the slide, said collapsible holding means including a wing fixed to the yoke and extending outwardly on either side from the yoke and disposed to be moved from an extended position generally normal to the axis of the tubular member to a collapsed position generally parallel to the axis of the tubular member as the slide is moved toward said opposite end portion of the tubular member, operating means associated with said opposite end portion and operably connected to the slide for moving the slide toward said opposite end portion to thereby pivot the yoke and move the wing to the collapsed position, and means operably connected to said collapsible holding means for pivoting the wing to the extended position as the slide is moved to the first named end of the tubular member.

4. A device for firmly holding the folded overlapping flaps of a partially filled container while the flaps are mechanically fastened together, comprising an elongated tubular member having an inner end disposed diagonally to the axis thereof and having a slot extending longitudinally thereof, a slide slidably disposed within the tubular member, a collapsible holding member, connecting means extending through said slot for pivotally connecting the central portion of the collapsible holding member to the slide, said collapsible holding member disposed to be pivoted from an extended position generally normal to the axis of the tubular member to a collapsed position generally parallel to the axis of the tubular member as the slide is moved toward the outer portion of the tubular member, an operating member connected to the slide to move the slide outwardly within the tubular member and thereby pivot the collapsible holding member to the collapsed position, said tubular member being adapted to be inserted within an opening between the folded flaps of the container when the collapsible holding member is in said collapsed position, and resilient means interconnecting the slide and the collapsible holding member for pivoting the collapsible holding member to the extended position as the slide is moved to the inner portion of the tubular member and thereby locate the holding member against the inner surface of the folded flaps in position to support the flaps for fastening.

5. The structure of claim 4 and including a wing member slidably connected with respect to the slide and including a wing extending outwardly through the slot and disposed generally normal to the axis of the tubular member, said wing member being located longitudinally of the collapsible holding member in a direction toward the outer end of the tubular member and disposed to engage the outer surface of the folded flaps while the collapsible holding member engages the inner surface of the folded flaps to thereby hold the flaps tightly between said members.

6. The structure of claim 1 in which the fixed holding member is displaced 90° with respect to the collapsible holding member in the extended position.

7. A device for firmly holding the overlapping flaps of

a partially filled container while the flaps are fastened together, comprising an elongated member having a first end portion adapted to be inserted within an opening between the folded flaps and having a second end portion adapted to be located outside of the container, a collapsible member connected to the first end portion of the elongated member and disposed to be moved from a collapsed position in general alignment with the axis of the elongated member to an extended position at an angle to said axis, means for collapsing said collapsible member to said collapsed position to enable the elongated member to be inserted within the opening between the flaps, means for moving said collapsible member to the extended position when said first end portion of the collapsible member is located within the container, and a holding member associated with the elongated member and extending outwardly from the elongated member at an angle to said axis, said holding member being located between said second end portion and said collapsible member and serving to engage the outer surface of the folded flaps when the collapsible member is in engagement with the inner surface of the folded flaps.

8. A device for firmly holding the overlapping flaps of a partially filled container while the flaps are mechanically fastened together, comprising an elongated member having an inner portion adapted to be inserted within an opening between the folded flaps and an outer portion

adapted to be located outside of the container, a collapsible member having the central portion thereof pivotally connected to said inner portion of the elongated member and disposed to be pivoted from a collapsed position in general alignment with the axis of the tubular member to an extended position at an angle to said axis, connecting means connected to the collapsible member and extending outwardly to the outer portion of said elongated member, an operating member connected to the outer portion of said elongated member for actuating said connecting means and pivoting said collapsible member to the collapsed position to enable the elongated member to be inserted within the opening between the flaps, a holding member associated with the elongated member and extending outwardly from the elongated member at an angle to said axis, said holding member being located between said collapsible member and the outer portion of said elongated member and serving to engage the outer surface of the folded flaps when the collapsible member is in engagement with the inner surface of the folded flaps, and means for biasing said holding member toward the collapsible member.
